RETORET CHARGING MACHINE

Jess E. Scouten, Medford, Okla., assignor to
Thomas P. Morrison, Blackwell, Okla.

Application April 16, 1941, Serial No. 388,897

5 Claims. (Cl. 214—18)

This invention relates to charging machines for zinc retorts or the like.

An object of this invention is to provide a charging machine including a pair of charging elements and means for raising or lowering the elements whereby they may be aligned with the retorts.

Another object of this invention is to provide a retort charging machine including a carriage, a pair of conveyors, a hopper movable with the conveyors and the carriage and an elevator for maintaining the hopper substantially filled.

A further object of this invention is to provide in a retort charging machine a pair of conveyors with a vertically adjustable carrier means for each and so that the conveyors may be disposed on the desired angle relative to the retorts.

A further object of this invention is to provide in a retort charging machine a conveyor or charging screw which is formed in a plurality of universally connected sections, and a tubular housing about the conveyor, the housing also being formed of a plurality of universally connected sections, so that the forward or charging end of the conveyor may engage in a retort irrespective of the variation in the angle between the retort and the conveyor.

A further object of this invention is to provide in a charger a movable hopper having a pair of charging conveyors extending therefrom and means in the hopper for feeding the material to the conveyors.

A further object of this invention is to provide a retort charger of this kind which includes a pair of charging members and means for raising or lowering said members so that selected pairs of retorts may be charged in one operation.

To the foregoing objects and to others which may hereinafter appear, the invention consists of the novel construction, combination and arrangement of parts as will be more specifically referred to and illustrated in the accompanying drawings, wherein is shown an embodiment of the invention, but it is to be understood that changes, variations and modifications may be resorted to which fall within the scope of the invention as claimed.

In the drawings:

Figure 1 is a detail side elevation of a retort charging machine constructed according to an embodiment of this invention.

Figure 2 is a detail top plan of the machine.

Figure 3 is a longitudinal section taken vertically through the machine,

Figure 4 is a detail rear elevation partly broken away and in section of the machine.

Figure 5 is a sectional view taken on the line 5—5 of Figure 1.

Figure 6 is a fragmentary sectional view taken on the line 6—6 of Figure 1.

Figure 7 is a sectional view taken on the line 7—7 of Figure 3.

Figure 8 is a sectional view taken on line 8—8 of Figure 1.

Figure 9 is a fragmentary longitudinal section taken through a portion of one of the charging elements, and

Figure 10 is a fragmentary sectional view 15 through the lower portion of the movable hopper showing the means for moving the hopper lengthwise of the frame.

Referring to the drawings, the numeral 15 designates generally a substantially rectangular frame structure which is provided with pairs of wheels 16, which are carried by axles 17 extending between the front and rear frame members 18 and 19 respectively. The frame members 18 and 19 are connected together at their opposite ends by end frame members 20 and 21. The wheels 16 are of the flanged type and are adapted to engage a pair of parallel rails 22, which are disposed along the front ends of the retorts, so that the frame structure 15 may be moved relative to the retorts in order to position the frame structure 15 in confronting relation with respect to the selected series of superposed retorts.

The movable frame structure 15 has secured thereto a pair of parallel beams or frame members 23, which are secured to the front and rear frame members 18 and 19 and project forwardly and rearwardly from the frame members 18 and 19, as shown in Figures 1 and 2. The beams or supporting members 23 each have secured to 35 the forward portions thereof upright frame members generally designated as 24. The upright frame members 24 each comprise a pair of vertically disposed guide members 25, which are secured, as at 26, to the beams 23 and the upper 40 ends of the uprights 25 are connected together by an upper bar or rail 27. The two front frame members 24 are connected together by means of connecting bars 28 and 29, which engage the rear 45 and front portions of the frame members 24.

A rear upright frame structure generally designated as 30 is secured to and extends upwardly from the beams or supporting members 23 and comprises a pair of vertical frame members 31, which are secured, as at 32, to the beams 23 and 55 are braced by angled bracing members 33 se-

cured to the beams 23 and the uprights 31 at a point upwardly from the lower ends thereof. The uprights 31 at the upper ends are connected together by a connecting bar 34.

A vertically movable charger supporting carriage generally designated as 35 is slidably carried by the frame members 24 and includes a pair of vertically disposed carriage members 36 and 37, which are connected together at their upper ends by connecting bar 38. A plurality of connecting plates 39, 40 and 41 are also connected between the uprights 36 and 37 and operate to maintain the uprights 36 and 37 in parallel relation. A pair of forwardly extending slide members 42 are secured to the forward uprights 36 and a lower forward pair of slide members 43 are secured to the uprights 36 and engage on opposite sides of the vertical guide members 25 at the forward portions of the front frame members 24. A pair of rearwardly extending plates or slide members 44 are secured to the upper portions of the rear uprights 37 and a lower pair of slide plates 45 are secured to the lower portions of the uprights 37 and engage on opposite sides of the rear frame members 25, so that the carriage 35 may freely be moved vertically within the front frame structure 24. In practice there are two of these carriages 35 on opposite sides of the front vertical frame structure 24, which are simultaneously movable in the vertical frame members 25, as shown in Figure 7.

The two charger supporting carriages 35 are adapted to be vertically moved and disposed in a selected vertical position within the frame structure 24 by means of a pair of cables 46 and 47, which have one end thereof secured to plates 48 and 49 respectively. The plates 48 and 49 are secured to the upper frame members 38. The cables or flexible members 46 and 47 are wound about winding drums 50 and 51 respectively, which are fixed to a winding shaft 52. The shaft 52 is journaled in bearings 53 and 54 which are secured to the upper frame members 27. A sprocket 55 is fixed to the shaft 52 and a chain or flexible driving member 56 is trained about the sprocket 55. A reversible electric motor 57 is mounted on the upper end of the frame structure 24 and has a sprocket 58 secured to the shaft 59 thereof. The sprocket 58 engages the chain or driving member 56 so that the winding drums 50 and 51 may be rotated in the desired direction to either raise or lower the frame members 35.

A charger supporting shaft 60 is journaled between the two plates 39, as shown in Figure 7, and has secured thereto a roller 61 having a concave charger engaging peripheral surface 62. A second charger supporting shaft 63 is journaled in the lower connecting plates 41 and has fixed thereto a charger supporting roller 64 having a concave charger engaging surface 65. A pair of rails 66 are pivotally connected at their front ends, as at 67, to the lower portion of the rear carriage frame members 37 and the rear ends of the rails 66 are pivotally connected, as at 68, to a rear vertically movable carriage, generally designated as 69. The rear carriage 69 includes a pair of vertical frame members 70, which are provided with vertically disposed pairs of spaced apart slide members 71 and 72, which engage on opposite sides of the rear uprights 31. The rear uprights 31 constitute guide members for the rear carriage 69. The rear carriage 69 is vertically adjusted relative to the rear guide members 31 by means of a pair of carriage raising

or lowering flexible members 73 and 74, which have an end thereof secured as at 75 and 76 to eyes carried by the side rails 70 of the carriage 69.

- 5 The flexible members 73 and 74 are wound about winding drums 77 and 78, which are fixed to a winding shaft 79. The shaft 79 is journaled in bearings 80 and 81 carried by the connecting bar 34 and a sprocket 82 is fixed to the 10 winding shaft 79. A flexible drive member 83 in the form of a chain is trained about the sprocket 82 and also about a motor sprocket or drive member 84 fixed to a motor shaft 85. The shaft 85 is connected with a reversible electric motor 86 supported by a bracket 87 extending rearwardly from the connecting member 34. In practice the rails 66 are disposed on an inclination to the horizontal as shown in Figure 1, this inclination being substantially the same inclination as the 15 inclination of the retorts.
- 20 A charging carriage generally designated as 88 is movably mounted on the rails 66 and includes a pair of side carriage members 89 which have secured thereto wheels 90 journaled on shafts 91. The carriage 88 also includes a pair of uprights 92 fixed at their lower ends to the lower carriage members 89 and the uprights 92 are connected together by means of connecting plates 93 and 94. A charging hopper generally designated as 95 has the rear wall 96 thereof secured 25 to the uprights 92 by fastening devices 97 and the hopper 95 also includes a pair of downwardly convergent bottom walls 98 and 99, which are connected at their lower or convergent ends to a U-shaped trough 100 extending transversely of the carriage 88.

30 The carriage 88 including the hopper 95 is adapted to be moved lengthwise of the rails 66 by means of a carriage moving chain 101. The chain 101 has one end thereof secured to the front wall 102 of the hopper 95, as at 103, and another end of the chain 101 is secured, as at 104, to the rear wall 96 of the hopper 95. The chain 101 is trained about a forward sprocket 105 which is fixed to a forward sprocket shaft 106. The shaft 106 is journaled in the plates 40 carried by the two vertically movable carriage members 35. In practice there are two of these chains 101 as shown in Figure 2 and two sprockets 105 on the forward shaft 106. The upper run of the chain 101 extends through the walls 96 and 102 of the hopper 95 and preferably a tubular guide member 107 is connected between the two walls 96 and 102 of the hopper 95 through which the upper run of the chain 101 loosely engages. It will be understood that there are two of these tubular guide members 107 as shown in Figure 2. The two chains 101 at their rear portions are trained about rear sprockets 108, which are fixed to a hopper moving shaft 109.

35 The shaft 109 is journaled in bearings 110 fixed to the rear carriage member 69. A driving sprocket 111 is fixed to the shaft 109 and has a flexible driving member 112 in the form of a chain trained thereabout. The chain 112 is also trained about a driving sprocket 113 carried by a shaft 114 connected with a reversible motor 115. The motor 115 is supported in rearwardly extended relation with respect to the vertically movable carriage 69 by means of a motor supporting bracket 116. The bracket 116 is fixed to one of the side frame members 70, as shown in Figure 4. The hopper 95 is provided with an upwardly flared upper end portion 117 and the hopper 95

is adapted to be substantially filled with the ore during the charging operation.

A lower charging tube or conveyor housing generally designated as 118 is fixedly connected at its rear end to the lower connecting plate 94. The tube or housing 118 is formed with a rear stationary tubular section 119, an intermediate tubular section 120 and a forward tubular section 121. The rear section 119 is connected with the intermediate section 120 by means of a universal connection 122 so that the intermediate section 120 may be disposed at a selected angle with respect to the rear section 119. The forward tubular member 121 is connected at its rear end to the forward end of the intermediate tubular member or section 120 by means of a universal connection 123. The rear tubular member 119 extends beneath the trough or guide member 100 and is provided with an opening 124 in its upper side which communicates with the interior of the trough or guide member 100. In this manner the material in the trough 100 will move downwardly into the opening 124 and will be discharged into the rear tubular member 119. A screw conveyor structure generally designated as 125 is rotatably mounted in the lower tube or housing structure 118 and comprises a rear rotatable screw conveyor member 126, which is rotatable in the stationary tubular member 119. The shaft 127 forming part of the conveyor 126 extends through a cap or bearing 128 at the rear end of the tubular member 119. An intermediate screw conveyor 129 is disposed in the intermediate housing 120 and is connected at its rear end with the rear conveyor member 126 by a universal connection 130.

The connection 130 is disposed within the universal connection 122, the latter connection being of a hollow construction. A forward screw conveyor 131 is rotatably disposed in the forward tubular section 121 and is connected at its rear end to the forward end of the intermediate conveyor 129 by means of a universal connection 132 disposed within the hollow universal connection 123. A sprocket 133 is fixed to the shaft 127 rearwardly of the cap or bearing 128, and a flexible drive member 134 is trained about the sprocket 133. A driving sprocket 135 carried by a motor shaft 136 also engages the chain or drive member 134 and the shaft 136 is operated by a motor 137. The motor 137 is supported between the uprights 92 by an L-shaped motor supporting member 138.

An upper conveyor housing generally designated as 139 is disposed in substantially parallel relation with the lower conveyor housing 118 and includes a rear conveyor section or member 140, an intermediate conveyor section or housing 141 and a forward conveyor housing or section 142. The rear conveyor housing 140 extends through the walls 96 and 102 of the hopper 95 and is also fixed to the supporting plate 93. A transversely disposed upper trough 143 is secured between the end walls 144 and 145 of the hopper 95 and is provided with a pair of upwardly divergent walls 146. The trough 143 is provided with an opening 147 in the lower portion thereof communicating with the conveyor housing 140, so that material from the trough 143 will be discharged into the rear stationary housing 140.

The intermediate conveyor housing 141 is connected with the rear conveyor housing 140 by means of a universal coupling 148 and the forward conveyor housing 142 is connected with the

forward end of the intermediate conveyor housing 141 by a universal coupling 149.

A screw conveyor structure generally designated as 150 is rotatably mounted in the housing 139 and includes a rear screw conveyor member 151 rotatable in the stationary housing member 140. The shaft 152 of the rear conveyor member 151 is journaled through a cap or bearing member 153 carried by the rear end of the housing member 140. The conveyor structure 150 also includes an intermediate screw conveyor 154, which is connected with the forward end of the rear conveyor 151 by means of a universal connection 155. A forward screw conveyor 156 is rotatable in the forward housing 142 and is connected at its rear end with the forward end of the intermediate conveyor 154 by means of a universal coupling 157. The universal couplings 155 and 157 are disposed interiorly of the hollow universal coupling members 148 and 149 respectively. The shaft 152 has fixed thereto a sprocket 158 about which a flexible drive member 159 is trained. The chain or drive member 159 is also trained about a second sprocket 160 mounted on the motor shaft 136.

The trough 100 at the lower portion of the hopper 95 has rotatably mounted therein a screw conveyor structure generally designated as 161. The conveyor structure 161 comprises a pair of reversely pitched conveyor members 162 and 163 mounted on the common conveyor shaft 164. The inner or confronting ends of the reversely pitched conveyor members 162 and 163 are spaced apart and are disposed adjacent the discharge opening 124 which opens into the lower conveyor housing 119. The opposite ends of the conveyor shaft 164 are journaled in bearings 165 and 166 carried by the end walls 144 and 145 of the hopper 95 respectively. An upper conveyor structure generally designated as 167 is rotatably mounted in the upper trough 143 and comprises a pair of reversely pitched conveyor members 168 and 169 mounted on a common conveyor shaft 170. The confronting ends of the conveyor members 168 and 169 are spaced apart as shown in Figure 5 and extend from the discharge opening 147 communicating with the rear conveyor housing member 140.

The opposite ends of the conveyor shaft 170 are journaled in bearings 171 and 172 carried by the hopper end walls 144 and 145 respectively. The shaft 170 at one end thereof has secured thereto a sprocket 173 about which a chain 174 is trained. The conveyor shaft 164 also has fixed thereto a sprocket 175, about which the chain 174 engages so that the two conveyors 161 and 167 may rotate as a unit. The shaft 170 also has fixed thereto a second sprocket 176 about which a chain 177 is trained. The chain 177 is also trained about a sprocket 178 carried by a shaft 179. The shaft 179 is journaled in a bearing 180, which is carried by an L-shaped supporting arm 181. The shaft 179 also has fixed thereto a bevelled gear 182, which is adapted to mesh with a second bevelled gear 183 carried by a shaft 184.

The shaft 184 is journaled in a bearing 185, which is carried by an L-shaped bearing supporting member 186. The bearing supporting member 186 is fixed, as at 187, to the rear wall 96 of the hopper 95 adjacent the upper portion thereof. The shaft 184 has fixed thereto a sprocket 188 about which a chain 189 is trained. The chain 189 also engages about a sprocket 190, which is fixed to the conveyor shaft 152. In this manner

the conveyors 125 and 150 will rotate as a unit with the charging conveyors 161 and 167.

In order to provide a means whereby the hopper 95 may be maintained in a substantially filled condition, I have provided an elevator structure generally designated as 191. The elevator structure 191 includes a substantially vertical or upright conveyor housing 192 connected with the upper end thereof a downwardly and inwardly inclined material guiding member 193. The material guiding member 193 is adapted to overlie the upper end of the hopper 95 so that the material elevated in the housing 192 will drop downwardly into the hopper 95. The conveyor or elevator housing 192 has movably mounted therein an endless conveyor structure including an endless belt 194 which is trained about a lower drum 195 and an upper drum 196.

The lower drum 195 is fixed to a shaft 197, shown in Figure 2, which at one end thereof is provided with a bevelled gear 198. The upper drum 196 is secured to an upper shaft 199 journalled in the upper portion of the housing 192. The belt or endless member 194 has fixed thereto a plurality of spaced apart transversely extending cleats or carrier members 200 so that as the belt 194 is moved in the housing 192 the material will be elevated by the cleats or carrier members 200 and discharged into the guide member 193. The lower end portion of the elevator housing 192 has secured thereto a laterally extending and upwardly opening hopper 201 into which the material is adapted to be discharged. The lower end of the conveyor structure including the belt 194 and the cleats 200 are extended into the lower hopper 201 so that material discharged into this latter hopper will be elevated and discharged into the hopper 95. A right angularly disposed shaft 202 is journalled in bearing members 203 and 204, which are fixed to the lower end of the elevator housing 192 and the shaft 202 has fixed thereto a bevelled gear 205 meshing with gear 198. The shaft 202 also has fixed thereto a sprocket 206 about which a chain 207 engages. The conveyor shaft 164 at the end thereof opposite from the sprocket 175 has fixed thereto a sprocket 208. The chain 207 engages about the sprocket 208 so that the elevator structure 194-200 will be operated simultaneously with the rotation of the shaft 164. The shaft 164 at its outer end may be journalled in a bearing 209 which is carried by the inner wall 210^a of the elevator housing 192. The housing 192 is fixedly secured to the end wall 145 of the hopper 95 by means of a pair of supporting brackets 210 and 211.

The brackets 210 and 211 are of substantially U-shape and have one leg thereof secured by fastening devices 212 and 213 respectively to the end wall 145. The other legs of the brackets 210 and 211 are secured as by fastening devices 214 and 215 to the inner wall 210^a of the elevator housing 192.

In the use and operation of this retort charging structure the frame structure 15 is adapted to be shifted to a position where the charging tubes 118 and 139 are in confronting relation to a pair of retorts. The charging tubes or conveyor housings 118 and 139 are adapted to be moved inwardly of the retorts by operation of the motor 115, which is adapted to shift the carriage 88 to the right as viewed in Figure 1. The vertical position of the combined conveyor and charging tubes 118 and 139 may be adjusted by means of the motors 57 and 86. In practice the normal operating posi-

tions of the conveyor housings 118 and 139 are the positions shown in the drawings in Figures 1 and 3. With the tubes 118 and 139 projected interiorly of the retorts, the conveyor members 125 and 150 may be operated so as to withdraw the material from the hopper 95 and force this material into the retorts. As the material is packed within the retorts the carriage 88 will be moved to the left so that the conveyors and the conveyor housings will be forced outwardly of the retorts during the charging operation. As the conveyors 125 and 150 are rotated so as to force the material lengthwise of the housings 118 and 139, the conveyors 161 and 167 will simultaneously be rotated to discharge the material from the hopper 95 into the conveyor housings 118 and 139. The hopper 95 is maintained in a filled condition at all times by operation of the elevator structure 191, which operates simultaneously with the operation of the several conveyors.

The universal joints of the charger members are tightened so that they are frictionally held, and the sections of the charger members will remain in axial alignment until some pressure is brought to bear which will overcome the frictional grip of the universal joints at which time they will be forced out of axial alignment. This factor prevents breakage if some of the retorts are not in exact alignment.

With a retort charging structure as hereinbefore described a pair of retorts may be charged in one operation and if more than two retorts are to be charged the vertically movable carriages 35 and 69 may be raised or lowered to the desired degree, so that the charging housings 118 and 139 will confront the desired retorts. During the time that the charging operation is taking place the elevator hopper 201 is adapted to receive the loose material from a supply source.

What I claim is:

1. In a retort charging machine a hopper, a plurality of superposed charger members directly communicating with said hopper, a support frame for said members, said hopper comprising a rectangular box-like construction having a flared open top and a centrally converging downwardly inclined bottom, a longitudinally extending casing located centrally of said bottom, a second longitudinally extending casing located parallel to and above said first named casing, and double opposed feed screws mounted in said casings and being adapted to feed material centrally of said casings to said charger members.

2. In a retort charging machine, a hopper, a pair of superposed charger members directly communicating with said hopper, one of said charger members passing through said hopper and the other of said charger members passing directly below said hopper, said hopper comprising a rectangular box-like construction having a flared open top and a centrally converging downwardly inclined bottom, a longitudinally extending casing located centrally of said bottom in communication with one of said charger members, a second longitudinally extending casing parallel to and above said first-named casing in communication with the other of said charger members, and a pair of double opposed feed screws mounted in said casings and being adapted to feed material centrally of said casings to said charger members.

3. In a retort charging machine of the type including a frame, a hopper mounted in the frame and means for moving the hopper hori-

zontally with respect to the frame; a charger member comprising an elongated sectional tube extending from said hopper through said frame, a sectional screw mounted for rotation in said tube, a universal joint operatively connecting the sections of said screw and a universal joint operatively connecting the sections of said tube, said universal joints being positioned equidistant from the outer end of said charger member outwardly of said frame, said charger member having its outer section solely supported by said universal joints whereby said outer section of said charger member may be deflected by a misaligned retort.

4. In a retort charging machine, a frame, a sectional tube extending outwardly through said frame, a sectional screw conveyor extending through said tube, a universal joint in said screw, and a universal joint in said tube, said universal joints operatively connecting said sections of said tube and said screw outwardly of said frame, said

universal joint of said screw having a concentric relation to the universal joint of said tube, said universal joints comprising the sole support of said outer sections of said tube and said screw and permitting said outer sections of said tube and said screw to be deflected by a misaligned retort.

5. In a retort charging machine, a frame, a sectional charger member comprising a plurality of tube members connected by a pair of universal joints and a plurality of screw conveyor sections operatively connected by a pair of universal joints, each of said universal joints of said screw having a concentric relation with the universal joints of said tube, one of the universal joints of said tube being positioned within said frame and the other being positioned outside of said frame, said pairs of universal joints coacting to permit deflection of said chargers on entering a misaligned retort.

JESS E. SCOUTEN.
